UNITED STATES PATENT OFFICE.

WILLIAM DENT PRIESTMAN AND SAMUEL PRIESTMAN, OF HULL, COUNTY OF YORK, ENGLAND.

METHOD OF WORKING HYDROCARBURETED-AIR ENGINES.

SPECIFICATION forming part of Letters Patent No. 397,517, dated February 12, 1889.

Original application filed July 20, 1887, Serial No. 244,802. Divided and this application filed March 9, 1888. Serial No. 266,689. (No model.) Patented in England December 21, 1886, No. 16,779; in Germany June 8, 1887, No. 43,273; in France June 25, 1887, No. 184,436; in Belgium June 23, 1887, No. 77,995; in Sweden July 6, 1887, No. 1,386; in Italy July 7, 1887, No. 421; in Cape Colony July 12, 1887; in Victoria July 19, 1887, No. 5,188; in Queensland July 22, 1887, No. 298; in New Zealand July 27, 1887, No. 2,449; in South Australia July 29, 1887, No. 848; in New South Wales August 2, 1887, No. 37; in Canada August 4, 1887, No. 44,936; in India August 15, 1887, No. 140; in Tasmania September 22, 1887, No. 492; in Brazil September 29, 1887, No. 504; in Spain November 15, 1887, No. 7,137; in Austria-Hungary December 3, 1887, No. 24,081 and No. 56,741; in Argentine Republic January 4, 1888, No. 634; in Norway March 7, 1888, No. 695, and in Portugal March 8, 1888, No. 1,223.

To all whom it may concern:

Be it known that we, WILLIAM DENT PRIESTMAN and SAMUEL PRIESTMAN, both subjects of the Queen of Great Britain, and residents of Holderness Foundry, Hull, in the county of York, England, have invented certain Improvements in Methods of Controlling the Action of Hydrocarbon-Engines, (for which we have been granted Letters Patent in Great Britain December 21, 1886, No. 16,779; in Austria-Hungary December 3, 1887, Nos. 24,081 and 56,741; in France June 25, 1887, No. 184,436; in Spain November 15, 1887, No. 7,137; in Belgium June 28, 1887, No. 77,995; in Norway March 7, 1888, No. 695; in Sweden July 6, 1887, No. 1,386; in Italy July 7, 1887, No. 421; in Cape Colony July 12, 1887, Reg. Folio 401; in Canada, application filed August 4, 1887, No. 44,936; in Victoria July 19, 1887, No. 5,188; in Portugal March 8, 1888, No. 1,223; in Germany June 8, 1887, No. 43,273; in Tasmania September 22, 1887, No. 492; in Queensland July 22, 1887, No. 298; in South Australia July 29, 1887, No. 848; in New South Wales August 2, 1887, No. 37; in New Zealand July 27, 1887, No. 2,449; in Brazil September 29, 1887, No. 504; in Argentine Republic January 4, 1888, No. 634, and in India August 15, 1887, No. 140,) of which the following is a specification.

This invention relates to a method of operating hydrocarbon-engines, whereby the supplementary air-charge, which is mixed with the hydrocarbureted-air charge, is varied in volume proportionately to the latter, in order that the working charge of explosive gases may be attenuated without being diluted with a disproportionate quantity of air. This may be accomplished by any suitable means. We have shown in the accompanying drawings the mechanism for this purpose illustrated and claimed in our pending application, Serial No. 244,802, of which this application is a division.

The drawings are merely employed herein for illustrative purposes.

Figure 1 of the accompanying drawings is a longitudinal sectional view of the vaporizer and valve mechanism of a hydrocarbon-engine adapted for supplying the fluids and liquids in proportionately-regulated quantities. Figs. 2 and 3 represent cross-sections of the plug-valve, and are designed to illustrate the peculiar form of ports therein.

For the better understanding of our method of controlling the feed of fluids and liquids to the vaporizer, we will first explain the construction and operation of the device illustrated in the drawings.

In a suitable valve-casing is mounted a plug-valve, *a*, on the stem of which is secured an operating-arm, *a'*, which is connected to the governor of the engine. (Not shown.) Through this medium the governor is made to control the valves. In the valve *a* are two ports, *b* and *b'*. (Seen, respectively, in Figs. 2 and 3.) These ports coincide with and form parts, respectively, of the air-passage *c* and hydrocarbon passage *c'*. Each of these passages is provided with a filtering-chamber, *d*, packed with cotton, wool, or other suitable filtering material, which strains the fluids on their way to the mixing-nozzle *e*. This nozzle, which we need not more particularly describe here, breaks the liquid hydrocarbon (arriving by passage *c'*) up into a fine spray and mixes it with the air, (arriving by way of passage *c*.) This mixture forms the hydrocarbureted-air charge. The form of the ports *b* *b'*, whereby the rotation of the plug by the governor gradually lessens the areas of the respective passages, is clearly illustrated in Figs. 2 and 3, and will require no further description.

The spindle of the valve *a* is prolonged, and on this prolongation *a'* is secured a butterfly or throttle valve, *g*, arranged to work within and to regulate the effective area of a passage, *c'*, through which the supplementary air-sup-

ply is admitted to the vapor-chamber. This supplementary air-supply is led from the passage c' into an annular chamber, h , surrounding the mixing-nozzle e , from which chamber it escapes into the vapor-chamber A on all sides through numerous perforations, h' . When the engine is running, any augmentation of its speed causes the governor to act on the valves a and g simultaneously, and thus to attenuate 5 the inflammable charge drawn into the engine-cylinder from the vapor-chamber, such attenuation being of course proportioned to the speed the engine has attained above the normal speed. The potency of the inflammable 10 charge is thus regulated at all times to suit the varying requirements of the work to be performed. As the supplementary air-supply is diminished and augmented proportionately to the supply of hydrocarbureted air, the 15 working charge is thus attenuated properly without being diluted. In this attenuation without dilution of the working charge consists the essential feature of our method of controlling this class of engines.

What we claim as our invention, and desire 25 to secure by Letters Patent, is—

The herein-described method of controlling the action of a motor-engine operated by the combustion of inflammable charges composed of air permeated with liquid hydrocarbon and 30 mixed with an additional quantity of air, substantially as described, said method consisting in automatically and simultaneously regulating the aforesaid three separate streams anterior to the vaporizing of the liquid hydrocarbon, whereby the resulting tri-part 35 working charge is, when necessary, attenuated without being diluted with a disproportionate quantity of air.

WILLIAM DENT PRIESTMAN.
SAMUEL PRIESTMAN.
